UNITED STATES PATENT OFFICE

172,301

POULTRY WATERER

Teddy J. Peterson, Lakewood, Colo.

Application September 24, 1953, Serial No. 26,942

Term of patent 7 years

(Cl. D12—2)

To all whom it may concern:

Be it known that I, Teddy J. Peterson, a citizen of the United States of America, residing at Lakewood, in the county of Jefferson and State of Colorado, have invented a new, original, and ornamental Design for a Poultry Waterer, of which the following is a specification, reference being had to the accompanying drawing, forming a part hereof.

In the drawing:

Fig. 1 is a perspective view of a poultry waterer, showing my new design; and

Fig. 2 is a slightly enlarged, end view thereof.

I claim:

The ornamental design for a poultry waterer, as shown.
